WATER-INSOLUBLE AZO-DYESTUFFS AND
FIBER DYED THEREWITH

Leopold Laska and Arthur Zitscher, Offenbach-on-the-Main, Germany, assignors to General Aniline Works, Inc., New York, N. Y., a corporation of Delaware

No Drawing. Application January 12, 1933, Serial No. 651,448, and in Germany January 18, 1932

10 Claims. (Cl. 260—95)

The present invention relates to new water-insoluble azo-dyestuffs and to fiber dyed therewith, more particularly it relates to compounds of the following general formula:

wherein R represents a radical of the benzene, naphthalene or anthraquinone series.

We have found that valuable water-insoluble azo-dyestuffs are obtainable by combining a diazo-, tetrazo- or diazoazo-compound which does not contain any group lending solubility, such as the sulfonic acid or carboxylic acid group with a 2'3'-hydroxynaphthoyl-2-amino-6-alkoxy-naphthalene, either in substance, on the fiber or on any of the usual substrata adapted for the production of lakes.

It is surprising that the dyestuffs obtainable according to the present invention, when compared with the dyestuffs which are obtained by using 2'3'-hydroxynaphthoyl-2-amino-naphthalene and 2'3'-hydroxynaphthoyl-2-amino-3-methoxy-naphthalene, respectively, are distinguished by an increased fastness to light.

The 2'3'-hydroxynaphthoyl-2-amino-6-alkoxy-naphthalenes may be obtained by condensing 2,3-hydroxynaphthoic acid with 2-amino-6-alkoxy-naphthalenes according to one of the usual methods.

The following examples serve to illustrate the invention, but they are not intended to limit it thereto, the parts being by weight unless otherwise stated:

(1) Well boiled and dried cotton yarn is padded with a solution containing per liter

2.25 grams of 2'3'-hydroxynaphthoyl-2-amino-6-methoxy-naphthalene,

45 15 cc. of caustic soda solution of 34° Bé and

10 cc. of Turkey red oil,

the yarn is thoroughly squeezed and developed in 50 a diazo-solution which contains per liter

1.21 grams of 1-amino-2,4-dimethylbenzene

and which has been neutralized by means of sodium bicarbonate, thereupon, the yarn is rinsed 55 and soaped while hot.

A saturated red dyeing of very good fastness to light is thus obtained.

The dyestuff corresponds to the following formula:

(2) By developing dehydrated cotton yarn which has been impregnated as described in example 1 in a diazo solution, which contains per liter

1.76 grams of 1-amino-4-methyl-2,3-dichlorobenzene, and which has been neutralized by means of sodium acetate, and by rinsing and soaping the yarn, there is obtained a bluish-red dyeing of very good fastness to light.

(3) 12.75 parts of 1-amino-3-chlorobenzene are dissolved in 34.2 parts of hydrochloric acid of 20° Bé and 250 parts of water and the whole is diazotized at about 10° C. by addition of a solution of 7 parts of sodium nitrite in 100 parts of water. The diazo-solution is run into a solution of 36 parts of 2'3'-hydroxynaphthoyl-2-amino-6-methoxy-naphthalene in 700 parts of water and 24 parts of caustic soda solution of 40° Bé, to which solution there has been added the quantity of sodium acetate sufficient for binding the excess of mineral acid and 15 parts of Turkey red oil. After the coupling has been finished, the dyestuff formed is filtered by suction and washed well. It may be used for the preparation of pigments, advantageously in the form of a paste. The dyestuff forms in the dry state a yellowish-red powder.

It yields when prepared in the usual manner on a substratum a reddish-orange pigment dyestuff.

(4) Cotton yarn which has appropriately been treated is impregnated with a padding solution which has been prepared in the usual manner and which contains per liter

2 grams of 2'3'-hydroxynaphthoyl-2-amino-6-ethoxy-naphthalene

and, after having dehydrated the yarn, it is developed in a diazo solution which contains per liter

1.68 grams of 1-amino-2-methoxy-4-nitrobenzene

and which has been neutralized by means of sodium acetate. Thereupon, the yarn is worked up as usual.

There is obtained a Bordeaux dyeing of a very good fastness to light.

The dyestuff corresponds to the following formula:

10

The dyestuffs may also be prepared on other fibers, as, for instance, on regenerated cellulose or on animal fibers, and may also be applied in the usual printing processes.

30 By using other diazo-, tetrazo- or diazoazo-
31 compounds, the process of the present invention
32 may be carried out in like manner.

The following table indicates a number of other combinations obtainable according to the present process but it does not comprise all possibilities for the preparation of dyestuffs by using different components; it, therefore, is not intended to limit the invention to the dyestuffs mentioned therein:

40

Diazotizing component	Coupling component	Tint
(1) 1-amino-3-chlorobenzene	2'3'-hydroxynaphthoyl-2-amino-6-methoxynaphthalene	
(2) 1-amino-2,5-dichlorobenzene	do	Reddish-orange
(3) 1-amino-2,4,5-trichlorobenzene	do	Brownish-red
(4) 1-amino-2-methyl-5-chlorobenzene	do	Orange-brown
(5) 1-amino-2-methyl-4-chlorobenzene	do	Red
(6) 1-amino-2-methyl-4-bromo-5-chlorobenzene	do	Saturated red
(7) 1-amino-3-methyl-4,6-dichlorobenzene	do	Deep bluish-red
(8) 1-amino-2-methoxy-5-chlorobenzene	do	Bluish-red
(9) 1-amino-2-phenoxy-5-chlorobenzene	do	Saturated red
(10) 1-amino-2-nitrobenzene	do	Yellowish-red
(11) 1-amino-3-nitrobenzene	do	Brownish-red
(12) 1-amino-4-chloro-2-nitrobenzene	do	Yellowish-red
(13) 1-amino-2-methyl-5-nitrobenzene	do	Brownish-red
(14) 1-amino-4-methyl-2-nitrobenzene	do	Clear yellowish-red
(15) 1-amino-2-methyl-4-nitrobenzene	do	Deep bluish-red
(16) 1-amino-2-methoxy-5-nitrobenzene	do	Brownish-red
(17) 1-amino-2-methoxy-4-nitrobenzene	do	Red
(18) 1-amino-4-nitronaphthalene	do	Bordeaux
(19) 1-amino-5-nitronaphthalene	do	Saturated
(20) 1-amino-5,8-dichloro-naphthalene	do	Bordeaux
(21) 4-amino-3-methoxy-6,4'-dimethyl-2'-nitroazobenzene	do	Do.
(22) 1-aminoanthraquinone	do	Blackish-currant
(23) 1-amino-4-benzoyl-amino-2,5-dimethoxybenzene	do	Brownish-red
(24) 4-amino-2,5-dimethoxy-4'-nitroazobenzene	do	Reddish-dark blue
(25) 1-amino-2,5-dichlorobenzene	2'3'-hydroxynaphthoyl-2-amino-6-ethoxynaphthalene	
(26) 1-amino-2,4,5-trichlorobenzene	do	Violet-black
(27) 1-amino-2-methyl-4-bromo-5-chlorobenzene	do	Brownish-red
(28) 1-amino-2-methoxy-5-chlorobenzene	do	Reddish-brown
(29) 1-amino-2-phenoxy-5-chlorobenzene	do	Yellowish-red
(30) 1-amino-4-chloro-2-nitrobenzene	do	Bluish-red
(31) 1-amino-4-methyl-2-nitrobenzene	do	Yellowish-red
(32) 1-amino-2-methyl-4-nitrobenzene	do	Yellowish-Bordeaux
(33) 1-amino-4 (2'-ethoxy-phenyl-1'-azo)-naphthalene	do	Bordeaux
		Do.
		Black

70 Since an object of the present invention is to provide dyestuffs of good fastness properties, which dyestuffs are insoluble in water and alkalies, it is to be understood that the aromatic nuclei of the general formulae appearing in the

series, yielding, when produced on the fiber, dyeings the shades of which vary from red to blue to black and being distinguished by good fastness properties, particularly by a good fastness to light.

75

3. The water-insoluble azo-dyestuff of the following formula:

yielding, when produced on the fiber, a Bordeaux
15 dyeing and being distinguished by good fast-
ness properties, particularly by a good fastness
to light.

4. The water-insoluble azo-dyestuff of the following formula:

30 yielding, when produced on the fiber, a clear yellow-red dyeing and being distinguished by

yielding, when produced on the fiber, an orange-brown dyeing and being distinguished by good fastness properties, particularly by a good fastness to light.

6. Fiber dyed with the azo-dyestuffs as claimed in claim 1. 95

7. Fiber dyed with the azo-dyestuffs as claimed in claim 2.

8. Fiber dyed with the azo-dyestuff as claimed in claim 3.

9. Fiber dyed with the azo-dyestuff as claimed in claim 4.

10. Fiber dyed with the azo-dyestuff as claimed in claim 5.
